UNITED STATES PATENT OFFICE.

EVERETT B. BRYANT, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

OPERATING MECHANISM FOR AUTOMATIC STOKERS.

1,416,547.

Specification of Letters Patent. Patented May 16, 1922.

Application filed July 11, 1919. Serial No. 310,237.

To all whom it may concern:

Be it known that I, EVERETT B. BRYANT, a citizen of the United States, residing in Philadelphia, Pennsylvania, have invented

5 Operating Mechanism for Automatic Stokers, of which the following is a specification.

One object of my invention is to provide novel mechanism particularly designed for use in stokers of the inclined underfeed type, 10 for feeding fuel to one or to a plurality of retorts from a source thereof such as a hopper;—the invention more particularly contemplating a novel combination of mechanical movement and reciprocable ram for each of the retorts whereby the fuel entering the ram chamber will be delivered therefrom to its retort at a substantially uniform rate and with the necessary force and certainty of action.

20 It is further desired to provide an automatic stoker including a plurality of retorts, with novel mechanism including devices for feeding fuel thereto whereby any or all of the retort-feeding devices may be 25 quickly and conveniently disconnected from the main driving mechanism at the will of the operator with a view to allowing accurate regulation of the amount of fuel delivered to the stoker.

30 Another object of the invention is to provide relatively simple means whereby the fuel feeding mechanism of any one or more of the retorts will be automatically disconnected from the main driving mechanism in 35 case of said feeding mechanism becoming choked or deranged;—the apparatus being constructed to permit of the operation of one or more of said devices without affecting the action of the others.

40 These objects and other advantageous ends I attain as hereinafter set forth, reference being had to the accompanying drawings, in which,

45 Fig. 1 is a vertical longitudinal section of a furnace having applied to it an inclined underfeed stoker equipped with my invention;

50 Fig. 2 is a horizontal section partly on the line 2—2, Fig. 1, further illustrating my invention;

55 Fig. 3 is a plan partly in horizontal section through the longitudinal center line of one of the ram chambers and on an enlarged scale, further illustrating my invention;

Fig. 4 is a vertical section on the line 4—4, 55 Fig. 3;

Fig. 5 and 6 are fragmentary vertical sections, illustrating details of my invention, and.

60 Figs. 7 and 8 are respectively a longitudinal section and a transverse vertical section illustrating the swivel nut and certain of its coacting parts.

65 In the above drawings 1 represents the setting of a boiler furnace having a bridge wall 3 and provided with a ram chamber 4 supported on a plate structure 2 at the front of the setting. The ram chamber structure not only supports the hoppers 5 but is also provided with projecting brackets 6, 7, 8 and 70 9 of which the first three support bearings for the main driving shaft 10. This shaft under operating conditions is constantly driven from a suitable source of power such as a sprocket chain 50 or equivalent structure through a wheel 12 fixed to said shaft.

75 In the present instance I have shown a stoker provided with two retorts 13 and 14 each having connected to it one of the ram chambers 4 and in each of these latter is operative a reciprocable ram 15 preferably having the form of a cylinder. This is held from rotating by a set screw or bolt 16 threaded into the bottom of the ram chamber and projecting into a longitudinally extending groove or key-way 17 in the ram. For reciprocating the rams from the driving

80 shaft 10, I mount on the forward or outer end of each of them a plate 18 having an elongated opening through which a diamond screw 19 is longitudinally movable. Said screw consists of a shaft or spindle provided with two oppositely inclined intersecting helical grooves constituting right and left hand threads joined or running together at 85 their ends. This screw is engaged by a swivel nut or equivalent device 20 carried by the plate 18 and is connected through a coupling 21 with a short shaft 22 to whose

90 forward end is fixed a flanged collar 23, the bracket 9 providing a bearing for said shaft and the coupling and collar cooperating with the ends of this bearing respectively to take the opposite longitudinal thrusts of the diamond screw 19.

100 105 Loosely mounted on the collar 23 is a bevelled gear 24 operatively connected to it by a shearing pin 25 extending into or lying

within a pair of hardened steel bushings 26 and 27 respectively mounted in the collar and in the gear. The teeth of this gear engage a bevelled pinion 28 loosely mounted 5 on the shaft 10 and having formed integral with it one part 29 of a jaw clutch, the second part 30 of which is keyed to said shaft. An operating lever 31 is suitably connected to this second clutch member so as to be capable of longitudinally moving it upon the shaft 10 into and out of engagement with the clutch member 29.

The stoker includes tuyere blocks 32 mounted on a tuyere box 33 below which is supported the wind box or air supply conduit 34. The inner or lower end of the tuyere box is supported on an auxiliary air box 35 for supplying the extension grate 38 and the latter with its actuating mechanism 15 is carried upon beams 36 and 37 supported on or forming part of the main frame structure of the stoker. Between said extension grate and the bridge wall 3 is mounted the dumping plate 39 whereby the ashes accumulating in the transverse pocket adjacent said bridge wall may be periodically dumped. Said plate is normally maintained in the position shown and is operable at will by suitable means constituting no part of the 20 present invention.

Under conditions of operation the driving shaft 10 is continuously rotated in one direction by power from a suitable source, connected through the chain 50 with the sprocket wheel 12, and if both of the clutches 29-30 be thrown in so that power is transmitted to the bevelled pinions 28, the two diamond screws 19 are continuously turned; the construction of the groove of each of 25 them being such that through the swivel nut 20 the rams 15 are moved alternately back and forth within their respective ram chambers. This action is due to the fact that said nut follows the thread of the screw 30 and is free to oscillate in its supporting structure 18 when, on reaching either end of said screw, its direction of motion is reversed by said thread. As a consequence, the continuous rotation of the diamond 35 screw in one direction causes a reciprocating movement of the nut and of the ram associated therewith.

The forward movement of each ram permits fuel to fall from the hopper 5 into the rear part of the ram chamber and the subsequent rearward movement of said ram forces said fuel into the adjacent retort and thence into the furnace where it is burnt with the air supplied from the wind boxes 34 and 35 through the tuyere blocks 32 and the extension grate 38.

By the use of the diamond screw it will be noted that the ram associated therewith

is forced rearwardly with each charge of fuel at a uniform and constant speed and is automatically moved forward after having reached the limit of its rearward movement, so that the fuel is delivered at the desired rate and in such manner that likelihood of the ram sticking or becoming clogged is reduced to a minimum.

If for any reason either of the rams should encounter some obstacle which would interfere with its movement, the abnormal stress on the driving mechanism would cause 75 shearing of its pin 25, thereby automatically disconnecting the shaft 22 from the bevelled gear 24 which actuates it, and preventing damage to the mechanism or its associated parts.

If for any reason it should be advisable or necessary to vary the rate of feed of the fuel to the furnace or to altogether stop it for a time, this end may be easily accomplished without interfering with the operation of the driving mechanism by operating either or both of the clutches 29-30 so as to stop feeding by either or both of the rams. When desired either or both rams may again be put in action.

I claim:

1. The combination in an inclined underfeed stoker of a retort; a ram chamber connected thereto and communicating therewith; a ram in said chamber; a removable plate secured to the forward head of said ram and formed with an elongated bearing therein; a diamond screw operative in the bearing; a nut mounted in said plate, having a portion projecting into the bearing in engagement with the diamond screw and free to oscillate to permit it to follow the thread thereof at its ends to cause reversal of the movement of the plate and ram; means for preventing rotation of the ram under the action of the screw; and means for rotating the screw to cause it to reciprocate the ram through the nut and plate.

2. The combination in an underfeed stoker of a retort; a ram chamber connected thereto and communicating therewith; a ram in said chamber; a bearing on said ram; a diamond screw operative in the bearing; a swivel nut mounted in said bearing with a portion projecting into and in engagement 115 with the diamond screw and free to oscillate in the bearing to permit it to follow the threads of said screw; means at the ends of the screw to cause reversal of the direction of movement of the bearing and ram; and 120 means for rotating the screw to cause it to reciprocate the ram through the agency of the nut.

In witness whereof I affix my signature.

EVERETT B. BRYANT.
